US00D532365S

(12) **United States Design Patent** (10) **Patent No.:** **US D532,365 S**
Shen (45) **Date of Patent:** **** Nov. 21, 2006**

(54) **BATTERY CHARGER**

(75) Inventor: **Chun-Liang Shen**, Ta Li (TW)

(73) Assignee: **E-J Electronics Co., Ltd.**, Ta Li (TW)

(**) Term: **14 Years**

(21) Appl. No.: **29/242,144**

(22) Filed: **Nov. 3, 2005**

(51) **LOC (8) Cl. 13-02**

(52) **U.S. Cl. D13/107**

(58) **Field of Classification Search** D13/107-110,
D13/118-119, 184; D14/251, 253, 432, 434;
320/107-115

See application file for complete search history.
